DOOR SEAL FOR FURNACES WITH PROTECTIVE ATMOSPHERE

Gerhard P. Lessmann, Wilkinsburg, Pa., assignor to Westinghouse Electric & Manufacturing Company, East Pittsburgh, Pa., a corporation of Pennsylvania

Application October 20, 1939, Serial No. 300,380

6 Claims. (Cl. 263—10)

My invention relates broadly to a furnace closure construction of general utility, but of particular application to heat-treating furnaces in which a charge is to be heat-treated while enveloped by an appropriate controlled gaseous atmosphere.

Treating processes of this character are well known, and the composition or constituents of the controlled gas are determined by the particular charge being heat-treated, and the particular method of heat-treatment to which it is being subjected. Hydrogen, dissociated ammonia, or partially or completely combusted hydrocarbon gases, are among the most common of the controlled atmospheres employed. Where such gases are used, their entire efficacy would be destroyed if outside air were permitted to leak into the heat-treating chamber or chambers of the furnace, and in order to minimize such leakage, the controlled gaseous atmospheres within the furnace are maintained at a pressure slightly above atmospheric, resulting in a plenum system. The higher pressure of the controlled atmosphere now causes the latter to leak out of the furnace through any cracks, crevices, or openings that are not perfectly sealed, and a small amount of leakage is generally desired in order to assure that no air finds its way into the furnace, and to continually flush out the heat-treatment chamber or chambers so that a clean and pure atmosphere is always contained in them.

However, leakage is necessarily a source of continuous waste and expense, and, therefore, furnace structures of the type described seek to minimize or decrease the leakage to as small an extent as possible.

The joint between the furnace door and the door jamb or frame generally has cracks or crevices through which gas may pass from the interior of the furnace to the outside, and vice versa. While cracks between the door and furnace door frame and consequent gas leakage or air infiltration may not be of serious consequence in large furnaces, which on account of their size contain a large volume of controlled gas and in which the work when heat treated is relatively far from the entrance, in the small furnaces, especially small box-type furnaces, small gas leaks or small amounts of air infiltration into the furnace become important in view of the proximity of the heat-treatment chamber to the furnace entrance and in view of its relatively small cubic content.

It is an object of my invention to improve the

seal between that part of the furnace which requires an opening in a furnace wall and the door therefor to the end that gas leakage either into or out of the furnace is kept down.

In accordance with the preferred embodiment of my invention, a resilient gasketing material, which is also heat-resistant to a considerable degree, such as, for example, asbestos fabric, is employed as a gasket between the door and the door frame. However, such resilient gasketing materials wear out very rapidly if rubbed repeatedly by the relative motion between it and the door or door frame. Accordingly, following my invention, I provide a door which first moves laterally from the door frame in its opening movement so that there is no rubbing contact on the resilient gasketing material in the subsequent opening movement of the door.

Accordingly, it is a further object of my invention to provide a gasketing material between the door and the door frame of a heat-treating furnace which will seal the crevices between the two and will have long life.

It is an additional object of my invention to so locate this resilient material that it is not directly exposed to the intense heat of the furnace. To this end the gasketing material is secured to the outer, cooler, rim edges of the door where it is maintained relatively cool.

My invention is especially adapted to high temperature furnaces and to this end both the door and the door frame are provided with expansion slots to prevent deformation due to warpage. By use of the gasket I assure a tight seal between the door and frame in spite of any irregularities of the contacting surfaces between the two which become greater with continued use of the furnace. I also employ the gasketing material to cover the expansion slots in the door so that there can be no gas leakage through them. Additionally, the gasket is so secured to the door that it can be readily replaced in the event that it ultimately becomes worn or has lost its efficiency as a seal.

Other objects and novel features of my invention will be apparent from the following description thereof, taken in conjunction with the drawings, in which:

Figure 1 is a schematic representation, in a side elevational view, of a small box type furnace to which my invention has been applied;

Fig. 2 is a schematic front elevational view of the furnace of Fig. 1;

Fig. 3 is an enlarged, elevational view of the door frame having cam means thereon for mov-

ing the door laterally in the beginning of its opening movement;

Fig. 4 is a side view of the structure of Fig. 3;

Fig. 5 is an enlarged horizontal sectional view through the door and door frame of the furnace;

Fig. 6 is an enlarged side view of the door with parts broken away and its refractory brick lining removed to show the essential features of its construction; and

Fig. 7 is an enlarged view of a detail showing the gasket and the manner by which it is secured to the door.

While my invention is applicable to any suitable type of furnace, in Figs. 1 and 2 I show a box-type furnace comprising the usual bottom wall 2, top wall 4, back end wall 6, front end wall 8, and side walls 10 and 12, these walls being constructed in the customary manner of a refractory inner lining backed by heat insulating brick or material.

The walls define a heat-treatment chamber 14 in which a charge is adapted to be heat-treated by suitable energy-charging means in the form of electrical resistors, radiant gas tubes, or any other suitable heating means. A gas inlet pipe 16 is adapted to convey a controlled atmosphere to the back end of the heating chamber 14 and passes through the brick work of the end wall 6 and also any outer, gas-tight, metallic shell which may be employed to encase the furnace, as is customary in the art. Charges are inserted into and removed from the furnace through a suitable opening 18 in the front wall 8 of the furnace. The front wall 8 is provided with a door frame or jamb 20 against which a furnace door 22 is adapted to abut for closing the opening 18. It may be observed that the front wall 8 is so constructed that the door frame is at a slight angle to the vertical for the purpose of having the weight of the door itself press its edges against the door frame.

Referring more particularly to Figs. 3 through 7, it may be perceived that the door comprises a plurality of channel members 24 which form the outer sides or edges of the door, the channel members having legs 26 on the side farthest from the furnace opening 18, and legs 28 on the side toward the furnace opening which are adapted to abut the door frame 20. The door in this particular embodiment is generally rectangular so that four channel members 24 are employed for the edge sides of the door with abutting corners being suitably welded together to form a gas-tight joint. The back of the door may comprise a sheet or plate of metal 30 welded or otherwise gas-tightly secured to the legs 26. Suitable refractory and insulating brick 40 fills the space within the metallic door casing formed by the channels 24 and plate 30, and may be anchored in position by well known expedients. A peep hole 42 may be provided in the door covered by a swinging plate 44 pivoted to the door at 46. Additionally, the bottom of the door may be provided with a plurality of spaced, reinforcing gusset plates 48. The door 22 is of a larger size than the opening 50 in the door frame which is aligned with the furnace opening 18 in the front wall 8, and the door legs 28 are at all points spaced outwardly a short distance from the edges of the opening 50 when the door is in its closing position.

For high temperature furnaces it is preferable to provide expansion slots in both the door frame and the door. To this end the door frame is provided with a plurality of spaced expansion

slots 52 extending from its outer edges for a short distance inwardly of the frame, and the channels 24 are similarly provided with expansion slots 54 extending from the inner rim, or the edge that is closest to the door frame, for a short distance towards its outer edge, preferably less than half the distance, these slots being provided in all of the channels 24 constituting the metallic edges of the door.

It is the main purpose of my invention to provide a suitable seal between the door and the door frame when the door is in closing position and to this end I secure gasketing material 56 to the outside surface of the door channels 24. This gasketing material is preferably asbestos fabric and is placed completely around the door edges, being held in place by angle members 58 bolted to the channel members 24 by a plurality of spaced bolts 60 screwed into suitable threaded holes 61 in the channels 24. The top and bottom angles 58 are substantially the same length as the corresponding horizontal edges of the door while the vertical angles 58 are of the same length as the vertical edges of the door.

As may be observed in Fig. 7, the gasketing material 56 is of a width somewhat greater than the length of the slots 54, having an edge 62 outwardly of the slots so that the slots are effectively covered by this material, and an additional edge 64 beyond the inner edge of the door for a purpose to be subsequently described. The angles 58 are formed with legs 66 somewhat longer than the slots 54 so that they will securely clamp the gasketing material 56 to the channels 24 beyond the ends of the slots 54 to prevent or at least minimize gas leakage through them. The other legs 68 of the angles 58 are placed slightly outward of the inner rim of the door so that they do not abut the door frame when the door is closed.

With the structure thus far described, with the door in closing position the edge 64 of the gasketing material 56 is compressed against the door frame 20 by virtue of the weight of the door itself and, where necessary, additional clamping means may be employed to force the door more tightly against its door frame. Accordingly, the edge 64 of the gasketing material provides a suitable gas seal between the rim of the door and the door frame which will follow irregularities in the abutting surfaces of the door frame or door, or both. Moreover, it may be observed that this gasketing material is fairly well shielded from the direct heat of the furnace and is substantially exposed to the outer, cooler, atmosphere about the door.

However, a compressible material suitable for gasketing as a rule wears very rapidly if rubbed and, accordingly, my invention further includes provisions for raising the door to opening position by first laterally moving the door away from the door frame so that the gasketing edge 64 is moved laterally away from the surface of the door frame and thereafter the door may be moved fully to open position without rubbing the gasket.

To obtain this operation with a vertically-moving door, the door frame 20 is provided at each of its vertical sides with cam and guide means indicated in their entirety by the reference numeral 70. This means comprises a cam bar 72 on each side of the opening 50, which, as shown in Fig. 4, has substantially straight flat surfaces between the points A and B, and the points C and D, and has two indentation grooves

74 between the points B and C and 76 between the points D and E.

The door is provided on each of its vertical sides with a pair of spaced cam shoes which ride on the surfaces of the corresponding cam bars 72. These shoes comprise a cam shoe 78 fitting the cam indent 74 and a cam shoe 80 fitting the cam indent 76. The shoes are suitably fastened to bars 82, in turn welded or otherwise secured to the vertical channel members 24 and reinforced by gusset plates 84 for securing a rigid assembly.

In operation the door 22 may be raised or lowered through the medium of a hydraulic or pneumatic cylinder 86 having a piston rod 88 to which one end of a sprocket chain 90 is secured, the chain passing over a sprocket wheel 92, with its other end secured to the upper bar 82 on the vertical side of the door, it being understood that two such chains are provided for each side of the door. Accordingly, in the closed position of the door, the cam shoes 78 are disposed in the cam indents 74 and the cam shoes 80 are disposed in the cam indents 76, the size of the cams and the depth of the indents being so chosen that the door presses against the door frame to compress the edge portions 64 of the gasket material 56. The cam guides may be further provided with additional protuberances 94 to position the door.

Inasmuch as the angle members 58 are secured to the outside of the door, it is necessary to dispose the cam shoes 78 and 80 at some distance from the door, and this means that the cam guide bar 72 must be correspondingly disposed. Accordingly, the door guide and cam means 70 further comprises vertically disposed bars 96 inward of the cam bars 72 and welded or otherwise secured thereto in any suitable manner, these guide bars being spaced outward somewhat from the door frame 20 and extending toward the door but beneath the cam shoes so that the door can be raised or lowered without excessive side play tending to displace the cam shoes from alignment with the cam guide bars 72.

In operation, if it is assumed that the door is in closed position, during initial upward movement of the door, the cam shoes 78 and 80 ride on the inclined surfaces 98 and 100 of their respective cam indents, the shoes having corresponding inclined surfaces to permit ready movement of the door. In riding on these inclined surfaces, the door is moved away from the door frame so that the edge portion 64 of the gasketing material 56 is moved laterally away from the door frame. After this initial movement of the door, the cam shoes 78 and 80 ride on the flat surfaces of the cam bar 72 between the points A and B, and C and D, respectively, until the door reaches its fully open position. In lowering the door, the reverse, however, takes place, that is, the shoes ride first on the higher flat surfaces of the cam bars and finally lodge in their cooperative cam indents. In this last movement, the weight of the door forces it against the door frame, thereby compressing the gasket edge 64 between it and the door frame for a tight seal.

It may be observed that I provide two shoes on each side of the door, the purpose of this being to prevent rocking of the door which might occur if one shoe only were used, which would, in such case, act as a pivot.

While I have described my invention in a preferred embodiment thereof, it is obvious that many changes may be made and equivalents ap-

plied thereto, which would come within the scope of my invention.

I claim as my invention:

1. A heat-treatment furnace having a heat-treatment chamber in which a charge is adapted to be heat-treated while enveloped by a special atmosphere, said furnace including walls defining a heat-treatment chamber, a metal shell about said walls, means to convey a special atmosphere into said chamber, said furnace being provided with an opening through which a charge may pass, a door frame about said opening, a door cooperating with said frame for closing said opening, said door having an exposed outer metallic casing provided with expansion slots extending from the face of said door which is adjacent said door frame, a resilient gasketing material, means for mounting said gasketing material for sealing the adjacent surfaces between the edge of said door and said door frame, said gasketing material having a sufficient extent to cover said slots, means for raising and lowering said door including cooperative devices on said door and door frame for moving said door to and from covering position for said opening with said gasketing material out of contact with said door frame except in extreme door closing position, and for laterally moving said door to or from its extreme closed position whereby to avoid rubbing contact of said material on said door frame.

2. A furnace closure means, preferably for a metal-encased furnace of the type in which a charge is to undergo heat-treatment while enveloped by a controlled gaseous atmosphere, comprising a door having a face adapted to face the furnace proper, said door having an outer metal casing with an open end at said face and a non-metallic refractory brick within said casing, said casing having spaced expansion slots extending from said face inward of said door, and a resilient gasketing material secured about the outside of said casing to cover said slots.

3. A furnace closure means, preferably for a metal-encased furnace of the type in which a charge is to undergo heat-treatment while enveloped by a controlled gaseous atmosphere, comprising a door having a face adapted to face the furnace proper, said door having an outer metal casing with an open end at said face and a non-metallic refractory brick within said casing, said casing having spaced expansion slots extending from said face inward of said door, and a resilient gasketing material removably secured about the outside of said casing to cover said slots, with an overlap extending slightly beyond said face.

4. A furnace closure means, adapted to be used for a metal-encased furnace of the type having a chamber in which a charge is to undergo heat-treatment while enveloped by a controlled gaseous atmosphere, comprising a door having an inner face adapted to face the furnace chamber, said door having an outer metal casing with an open end at said face and a non-metallic refractory brick within said casing, said casing having spaced expansion slots extending from said inner face and a resilient gasketing material secured to said casing to cover said slots, with an overlap extending slightly beyond said face.

5. A furnace closure means, adapted to be used for covering and uncovering an opening in a metal-encased furnace of the type having a chamber in which a charge is to undergo heat-treatment while enveloped by a controlled atmosphere, comprising a door having an outer

metal casing having a substantially open end facing said opening and a non-metallic refractory brick within said casing, the outer periphery of said casing at said opening substantially encompassing said opening, a resilient gasketing material about the outside portion of said casing at said periphery, and loosenable bar means for clamping said resilient gasketing material between said loosenable bar means and said casing, with an overlap extending slightly beyond said 10 casing in the direction of said opening.

6. In a furnace, wall means for providing a substantially enclosed furnace-chamber having an opening in one wall thereof, a door-frame for said opening and a movable door for covering 15

said opening, characterized by said door comprising a refractory wall-portion and a metallic portion enclosing at least the side edges of the refractory wall-portion, said metallic portion of the door having expansion slots therein extending from the surface thereof which is presented towards the furnace-chamber when the door is in its closed position, a gasket-member, and means for mounting said gasket-member so that it substantially seals the space between said door and said door-frame when the door is closed, said gasket-member having a sufficient extent to cover said expansion slots.

GERHARD P. LESSMANN.
